UNITED STATES PATENT OFFICE.

GEORGE H. BEHAN, OF SAN FRANCISCO, CALIFORNIA.

COMBINED NAPKIN RING AND HOLDER.

SPECIFICATION forming part of Letters Patent No. 236,207, dated January 4, 1881.

Application filed May 22, 1880. (No model.)

To all whom it may concern:

Be it known that I, GEORGE H. BEHAN, of the city and county of San Francisco, in the State of California, have made and invented a new and useful Improvement in a Combined Napkin Ring and Holder; and I do hereby declare that the following is a full, clear, and exact description of the same, reference being had to the accompanying drawings.

10 My invention relates to a novel construction of napkin-ring which is convertible at pleasure into a holder or a means for attaching and supporting the napkin on the clothing. It has for its object to provide a cheap, simple, 15 and serviceable device in which the ring for a napkin and a holder are combined in one article.

This invention contemplates improvements in a combined napkin ring and holder; and it 20 consists of two loops or bands pivoted together at one of their ends, and adapted to turn in upon each other, and provided with a boss and socket at their other ends, substantially as hereinafter more fully set forth.

25 In the accompanying drawings, Figure 1 shows my improved ring in perspective. Fig. 2 shows the same when converted into a support or holder for a napkin. Fig. 3 shows the two parts of which it is composed.

30 The two bands A A' are made preferably of a flattened U-shape form and tapering at the ends, as thereby presenting a symmetrical appearance and giving a somewhat pointed end to engage with a button-hole, the collar-band, 35 or other convenient part of the clothing. Two of these ends, a a, turn upon the pivot-joint e, that secures them together, and the opposite ends, b b, are lapped over each other, but not permanently connected. These ends, however,

are held in position and caused to turn upon 40 each other by means of the projection or boss d upon one and the cup-shaped socket e upon the other end, into which the boss d fits. The elasticity of the two bands holds these parts 45 d e one within the other, and thus the bands 50 can be turned into line, or else folded in upon each other, as shown in Figs. 1 and 2, respectively. This boss and its socket form the means by which the napkin is clasped and held when inserted between the ends b b, and the elastic 55 quality of the two bands acts to press them together, and so retain the napkin in place. As thus arranged and connected together these two bands or loops constitute in one article a napkin-ring of attractive appearance and a 60 strong and practical attachment by which to suspend the napkin properly in front of the clothing. The elasticity of the bands acts to hold them in line with each other and present a ring for the napkin, and when folded together the ends a a constitute a ready means 65 for engaging the holder with parts of the clothing.

Having thus fully described my invention, what I claim, and desire to secure by Letters 70 Patent, is—

In a combined napkin ring and holder, the loops or bands A A', pivoted together at the ends a a, and adapted to turn in upon each other, and provided with the boss d and the 75 socket e at their other ends, substantially as and for the purpose set forth.

Witness my hand and seal.

GEO. H. BEHAN. [L. S.]

In presence of—

EDWARD E. OSBORN,
WM. F. CLARK.
